UNITED STATES PATENT OFFICE.

CHARLES S. THOMAS, OF SAN DIEGO, CALIFORNIA.

TOOL-CO尤LING MEANS.

Application filed February 26, 1927. Serial No. 171,223.

My invention relates to couplings, more particularly to coupling means for tools such as braces and bits or the like, and the objects of my invention are: first, to provide 5 a device of this class in which the tool may be easily and quickly clamped by the tool coupling and easily and quickly released thereby; second, to provide a device of this class in which the parts are reduced to a 10 minimum and yet provide a rigid, strong and substantial coupling; third, to provide a device of this class in which the tool will not loosen but will hold the tool rigidly and in alinement even when roughly used; fourth, 15 to provide a device of this class which provides a positive grip on the tool; fifth, to provide a tool coupling of this class in which the parts may be made small enough so that it can readily follow an extension drill of 20 ordinary size, and sixth, to provide a device of this class which is economical of construction, sturdy, durable, and which will not readily deteriorate or get out of order.

With these and other objects in view, as 25 will appear hereinafter, my invention consists of certain novel features of construction, combination and arrangement of parts and portions, as will be hereinafter described in detail and particularly set forth in the 30 appended claims, reference being had to the accompanying drawings and to the characters of reference thereon, which form a part of this application, in which:

Figure 1 is an elevational view of my tool 35 coupling means in its operative position; Fig. 2 is a sectional view thereof through 2-2 of Fig. 1, with parts and portions shown in elevation to facilitate the illustration; Fig. 3 is a sectional view on an enlarged scale 40 through 3-3 of Fig. 2, with parts and portions shown in elevation to facilitate the illustration; Fig. 4 is an end view from the line 4-4 of Fig. 2 with the bit or tool removed; Fig. 5 is a rear end view of the tool, 45 and Fig. 6 is a fragmentary elevational view on a plane with 6-6 of Fig. 3 and with the outer sleeve removed.

Like characters of reference refer to similar parts and portions throughout the several views of the drawings.

The brace shank member 1, bit member 2, inner sleeve member 3, outer sleeve member 4, and pin member 5, constitute the principal parts and portions of my invention.

The brace member 1, of which only a fragment is shown, may be either power or

hand driven. Near the extremity of the brace member 1 is a transverse round hole 1^a with a V-shaped cutout portion 1^b extending to the extremity of the brace member, as 60 best shown in Figs. 2 and 4 of the drawings. The end of the bit member 2 is tapered and square. Its extremity is cut away, leaving a rounded portion 2^a and a flat V-shaped portion 2^b, which coincide with the portions 65 1^a and 1^b of the brace member 1, respectively, as best shown in Figs. 2 and 5 of the drawings. The sleeve member 3 slides over the joint between the brace member 1 and the bit member 2 and has a square tapered aperture 3^a at its extremity, which receives the bit 2. This square portion merges into the central circular hole 3^b, which extends the rest of the length of the sleeve. The inner sleeve member 3 is also provided with slots 70 75 3^c, which receive the pin 5, which is rigidly secured in the hole 1^c of the brace member 1. The slots 3^c and the pin 5 take the strain off the joint between the members 1 and 2. The brace end of the sleeve 3 is provided with 80 threads 3^d. These threads are tapered, as best shown in Figs. 2 and 6 of the drawings. The sleeve 3 is also provided with a plurality of slots 3^e in spaced relation, which extend the length of the threads 3^d and permit the sleeve portion between said slots 3^e 85 to be forced against the brace member 1 by the tapered portion of the outer sleeve member 4. The outer sleeve member 4 fits over the inner sleeve member 3 and has a threaded 90 portion 4^a, which is tapered to coincide with the taper of the threads 3^d. Thus, the threaded portions 4^a and 3^d serve as wedges. Therefore, by screwing the outer collar member 4 onto the inner collar member 3, the 95 threaded portions 3^d of the collar member 3 are forced against the brace member 1 and grip it securely. To place a bit in this coupling means the outer collar member 4 is loosened so that the inner collar member 100 3 does not grip the brace 1 and the two collar members are slipped back on the brace 1 until they assume the position shown by the dotted lines in Fig. 2 of the drawings. The portions 2^a and 2^b of the tool are slipped into 105 the portions 1^a and 1^b, respectively, the two collar members are slipped back until the inner collar member fits snugly around the bit end, the outer collar member is turned so that the inner collar member is forced against the 110 brace member 1, and the device is then ready for use.

Though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

10 Having thus described my invention, what I claim as new and desire to secure by Letters Patent is:

1. A device of the class described, including a brace shank provided with a dovetail female portion, a tool provided with a conforming dovetail male portion, a plurality of concentric slidably mounted sleeves on said shank, and screw and taper means in connection with said sleeves for locking said concentric sleeves over the joint of said shank and tool.

2. A device of the class described, including a shank, a tool, means for interlocking said shank and tool, a plurality of concentric slidably mounted sleeves on said shank, and means for locking said concentric sleeves over the joint of said shank and tool, said locking means consisting of tapered threads between said concentric sleeves and means for turning the outer sleeve in relation to the inner sleeve.

3. A device of the class described, including a shank with a cutout V-shaped slot in said shank with a cutout circular portion at the apex of said V-shaped slot, a tool with a V-shaped and cylindrical portion adapted to coincide with said V-shaped and circular cutout portion of said shank, a plurality of concentric sleeves slidably mounted on said shank, and means for locking said sleeves over the joint of said tool and shank.

4. A device of the class described, including a shank with a cutout V-shaped slot in said shank with a cutout circular portion at the apex of said V-shaped slot, a tool with a V-shaped and cylindrical portion adapted to coincide with said V-shaped and circular cutout portion of said shank, a plurality of concentric sleeves slidably mounted on said shank, and means for locking said sleeves over the joint of said tool and shank, said locking means consisting of tapered threads between said concentric sleeves, and means for turning the outer sleeve in relation to the inner sleeve.

5. In a tool coupling, a shank and a tool interlocked with each other, an inner sleeve mounted over the joint provided with a tapered square-shaped portion at one end

adapted to fit the shank of the tool and with a tapered, externally threaded, slotted portion at its other end and provided with slots longitudinally in its sides, a pin mounted in said shank and extending into said slot, and an outer sleeve adapted to fit over said inner sleeve and provided with internal tapered threads adapted to fit the external threads of said inner sleeve.

6. In a tool coupling, a shank provided with a transverse hole therethrough and with a V-shaped opening extending therefrom, a tool shank provided with a conforming rounded and V-shaped portion adapted to fit tightly therein, an inner sleeve provided with a tapered square-shaped portion at one end and with a tapered, externally threaded, slotted portion at its other end and provided with slots in its sides, a pin mounted in said shank and extending into said slot, and an outer sleeve adapted to fit over the inner sleeve and provided with internal tapered threads adapted to fit the external threads of said inner sleeve.

7. In a tool coupling, a brace shank and a tool interlocked with each other, an inner sleeve mounted over the joint provided with a tapered portion at one end adapted to fit the tapered shank of the tool and with an externally tapered portion at its opposite end provided with slots in its sides, key means connecting said sleeve with said brace shank to prevent relative rotary movement, and an outer sleeve adapted to fit over said inner sleeve and provided with an internal tapered portion adapted to engage and contract the external tapered portion of said inner sleeve.

8. In a tool coupling, a brace shank and a tool interlocked with each other, and inner sleeve means mounted over the joint provided with a portion at one end adapted to fit the shank of the tool and with a slotted tapered portion near its one end and with an externally threaded portion at said end, key means connecting said brace shank and inner sleeve means to prevent relative rotary movement, and an outer sleeve adapted to fit over said inner sleeve and provided with an internal tapered portion adapted to engage said external tapered portion on said inner sleeve means and provided with internal threads adapted to fit the external threads on said inner sleeve means.

In testimony whereof, I have hereunto set my hand at San Diego, California, this 17th day of February, 1927.

CHARLES S. THOMAS.
